UNITED STATES PATENT OFFICE.

WILLIAM HENRY SKERRITT, OF JERSEY CITY, NEW JERSEY.

ELEVATOR-HATCHWAY COVER.

SPECIFICATION forming part of Letters Patent No. 311,684, dated February 3, 1885.

Application filed August 18, 1884. (No model.)

To all whom it may concern:

Be it known that I, WILLIAM HENRY SKERRITT, a citizen of the United States, and a resident of Jersey City, in the county of Hudson and State of New Jersey, have invented certain new and useful Improvements in Elevator-Hatchway Covers, of which the following is a specification.

The object of my invention is to provide an improved manner and means of hinging and operating the hatch-covers in the several floors of a building through which an elevator runs, and which shall obviate the necessity of making such covers in two separate parts, in order to enable them to be raised and lowered without interfering with the elevator guide-posts, and by which all the covers of the hatchway may be opened or closed simultaneously and with uniform resistance to the force applied in hoisting, regardless of their angle of elevation. For these purposes the invention comprises a hinging device by which the cover, when being raised, receives a lateral as well as the ordinary vertically-circular movement, and is thus slid away from possible contact with the guide-posts, thereby enabling it to be raised from the horizontal to a fully-vertical position, so as to allow the elevator to pass it; also, the combination, with a chain or rope having a counter-weight and connected by branch chains or ropes to all the covers of the same hatchway, of a winding-drum formed of a double fusee, or of one increasing and one decreasing arithmetically spiral groove, and suitable gearing whereby the leverage of the force applied is varied in exact proportion to the weight, thus rendering the resistance and the required force uniform.

The invention will be fully explained in the following description with reference to the accompanying drawings, in which—

Figure 1 represents a plan view of my hatch-cover closed, the vertical posts being shown in section taken on line $x x$ of Fig. 2. Fig. 2 is a side view with the hatch-door open, and seen in the direction of arrow 1 of Fig. 1. Fig. 3 is a general elevational view, showing a series of hatchway-covers partly opened and the manner of connecting them so as to be operated simultaneously. Fig. 4 is a detail section on line $y y$ of Fig. 2, looking down in the direction of arrow 2, and showing the device by which the cover receives a lateral or sliding movement by being turned on its hinges.

A is one of the hatch-covers.

B B' are the guide-posts for the elevator, the elevator and its suspension-rope being shown in Fig. 3, and designated by the letters $b b'$, respectively.

C is the chain or rope by which the covers A are raised.

In order to operate all the covers simultaneously I secure the lower end of the chain C to the first or lowest cover, A, and thence run it underneath and partly around a pulley, d , in or at the side of the hatchway, thence bring it up above and partly around a larger pulley, D, underneath the roof or top floor of the building, thence down, as indicated by C', to the ground-floor, where its end is secured to the winding-drum or windlass. Thence a chain, C², attached with its lower end to the said drum, is carried up above and partly around a pulley, D', similar to the pulley D, and arranged suitably near to the latter, thence down again a sufficient distance to allow attaching to it a weight, E, counterbalancing the combined weights of the covers and pieces of chain not balanced by the chain itself. Each cover above the first one is then connected to the chain C by an auxiliary or branch chain, e, running underneath and partly around side pulleys, d' , similar to the pulley d , before described. The chains c and pulleys d' are so arranged that when the covers are raised in their vertical position the point of attachment of the chain c to the main chain C has about reached the under side of the next ceiling above. Where this cannot be conveniently done with the uppermost cover, owing to the location of the pulley D too far below the uppermost ceiling, I carry the chain c above and partly around the pulley d' , thence down underneath and partly around another pulley, e, before I secure its end at c' to the chain C, thereby allowing the point of attachment c' sufficient travel to raise the cover in a vertical position before reaching the pulley D.

F is the winding-drum, its shaft being mounted in suitable bearings upon posts G, or other frame-work, and provided with a cog-wheel, H, in which is geared a pinion, I, having a winch, J, upon the end of its shaft, wherewith to turn it and to revolve the drum F with an effect proportional to the difference in size between the said pinion and wheel I and H. The drum C is composed of two fusees or cones having each a spiral groove upon its

surface, and joined together at the base. The chain C' is secured to the drum F at its smallest diameter, or at the beginning of the spiral groove on the fusee f , and similarly is attached 5 to the fusee f' the chain C^2 . The chains are wound relatively to each other, as in Fig. 1, the chain C^2 winding off from the largest diameter of the fusee f' , while the chain C' at the same time begins to wind on from the smallest diameter 10 of the fusee f , and vice versa, when the movement is in the opposite direction. The effect is that when the covers are down in their horizontal position, thus requiring the greatest power to raise them, their weight is acting 15 upon the smallest lever or radius of the drum, while the counterbalancing-weight E is acting upon the largest lever or radius of the said drum, and gradually as the covers ascend, and thus give less resistance, their leverage on the 20 drum increases, while at the same time the leverage of the weight decreases in the same proportion, and thus the power needed to be applied on the winch J is uniform, regardless of the variation in the angle of elevation of the 25 covers A .

In order to enable elevator-hatchway covers to be swung open without interfering with the posts B , they have generally heretofore been made in two separate parts by dividing 30 the cover diagonally from one post to the other; but to obviate making the cover in two parts and yet enable them to be raised clear of interference with the posts B , I provide the following simple construction: The hinge-pins 35 h are secured to lugs on a plate, i , fastened to the floor or frame-work at the side of the hatch, and the straps g , movable upon the said hinge-pins h , are secured to the cover A , (or the pin and plate h i may be attached to the cover and 40 the strap to the floor.) The hinge-pin is made as much longer than the width of the strap as the distance marked a in Fig. 1—that is to say, as the length of the lateral movement of the cover needed to make it clear the post B . 45 The rise of the front edge of the cover A needed to clear the post B farthest away from the hinges being as many times more rapid than the rise of the cut-out rear edge at a as the measure marked a^2 is times larger than 50 the measure a' , and the eye of the hinge being a little above the surface of the cover when closed, the front edge will have risen sufficiently to allow it to be ready to clear the post B by a lateral movement before the cut-out 55 rear edge has risen sufficiently to become perceptibly nearer the post B . A slot, a^3 , curved to correspond with the combined lateral and vertical movement, is cut in the cover from the central hole through which the suspension- 60 rope b' passes, and clear out to the front edge, so as to prevent interference with the rope or cable b' . To effect a lateral movement I swivel by a pin, m , through a plate, N , secured to the post B of the stationary support, a lug, M , 65 and in a similar manner by a pin, m' , through a plate, N' , secured to the cover A , I swivel

a lug, M' ; to the said lugs M M' , I hinge the jaws L L' , respectively, (see Fig. 4,) and to the said hinge-jaws I swivel by pins k a rod, K . By arranging the swivel-pin m a distance 70 above the hinge-pins proportionate to the length of the lateral movement required, and attaching the other swivel, m' , to the cover an equal distance from the hinge-pin, so that when the cover is open, as in Fig. 2, the 75 hinge-pin h and the rod K will be about parallel with each other and lie in about the same plane, the end of the rod K , which is attached to the jaw L' , will describe a circular curve, or rather a curve such as is formed by the intersection of a cone and a sphere having the same center, on the downward movement, pulling the cover to slide toward the left on the hinge-pins, and on the upward movement of the cover pushing it toward the right the 80 required distance, a .

Instead of by the rod K the lateral movement might be produced by hinging the strap g upon a hinge-pin having a spiral groove or thread; but the large pitch required of the 90 said thread in order to produce the large lateral movement required from a very small turn of the hinge would make such a device attendant with too much friction to be practical.

95 Other devices may be employed, but that shown in the drawings is the most practical and works to perfect satisfaction.

Having thus described my invention, what I claim as new, and desire to secure by Letters 100 Patent, is—

1. In combination with a hinged hatch-cover, A , and a stationary part of the hatchway, the lugs M M' , swiveled, respectively, to the said stationary part and to the said cover, 105 the jaws L L' , hinged to the said lugs M M' , respectively, and the rod K , swiveled with its ends to the said jaws, the pintles of the said hatch-cover hinges being sufficiently longer than the hinge-straps to allow of the lateral 110 movement desired, substantially as and for the purpose set forth.

2. The combination of one or more or a series of hatchway-covers, A , a winding-drum, F , consisting of two fusees, f f' , and two 115 ropes or chains, C C^2 , suspended on suitable pulleys, D D' , the rope C being attached to the said covers, and with one end to one of the said fusees, and the rope C^2 being attached with one end to the other fusee, and having 120 a counter-weight, E , attached to its free pendant end, substantially as and for the purpose set forth.

In testimony that I claim the foregoing as my invention I have signed my name, in 125 presence of two witnesses, this 13th day of August, 1884.

WILLIAM HENRY SKERRITT.
